UNITED STATES PATENT OFFICE.

JOHN H. GAGE, OF CHICAGO, ILLINOIS.

CAR-COVER.

SPECIFICATION forming part of Letters Patent No. 316,536, dated April 28, 1885.

Application filed November 24, 1884. (No model.)

To all whom it may concern:

Be it known that I, JOHN H. GAGE, of Chicago, in the county of Cook and State of Illinois, have invented certain new and useful 5 Improvements in Car-Covers, of which the following is a description, reference being had to the accompanying drawings, in which—

Figure 1 is an end view of a car to which my improved cover has been applied. Fig. 2 is a transverse vertical sectional view of the same. Fig. 3 is a side view in detail of one of the levers for operating said cover, the same having a counterpoise applied thereto, and being a modification of Fig. 1; and Fig. 4 is 15 an end view of the same.

Like letters of reference indicate like parts in the different figures.

The object of my invention is to provide a freight-car which may be especially adapted 20 for use in the carrying of coal and other like material in bulk, said car being so arranged that a permanent runway or foot-board may be had thereon, while the covers may be raised by means of suitable levers or equivalent 25 mechanism, whereby a sufficient portion of said car may be exposed for the purpose of loading and unloading the same, substantially as hereinafter more particularly specified.

In the drawings, A represents the body of 30 an ordinary coal or open car, the ends of which, A' A', (one only of which is shown in the drawings,) are made higher at the middle and slope down to the sides in the manner shown.

Permanently secured to the end boards, and 35 extending from one end of said car to the other, is a walk or running-board, B, of suitable width to enable the attendants to pass from one car to another in the usual way, and to stand thereon while operating the brake C. 40 A stationary guard-rail, D, Fig. 2, is preferably attached to said car by means of the rigid posts or uprights d. To firmly sustain said running-board and prevent the same from sagging, I place one or more supports or braces, 45 E, beneath the same, said supports being preferably made of channel-iron, and provided with cross ties or braces e, to strengthen said supports and enable them to withstand the shock of large lumps of coal or other materials 50 that may be loaded in said car from a chute. The bars e, instead of being placed horizon-

tally, may be crossed, if preferred, or otherwise arranged to suit the purpose for which the same are intended.

Secured to the ends A' A', and extending 55 lengthwise of the car beneath the running-board B, I place shafts F F, which I prefer to make from wrought-iron pipe, as combining greater lightness and strength. Pivoted upon said shafts F F at the respective ends of the 60 car are bent levers or arms G G, to which and to said shafts are rigidly secured covers H H. To the opposite extremities, g g, Fig. 1, of said levers are attached chains I I, connected with shafts J J, provided with hand-wheels K K, 65 which may be upon both ends of the car, or only upon one end if counter-weights are used at the other, as hereinafter stated. I prefer also to extend said chains, as at i i, to connect with those portions of the arms G to which the 70 covers are attached, so that said covers may be held down, if desired, by means of the shafts J J, which may be locked in any well-known manner.

Suitable ratchets and pawls are provided 75 upon the shafts J J behind said hand-wheels, and hence not shown in said drawings, for the purpose of holding said cover in any desired position. The turning of the hand-wheels K causes the chains I to wind upon the 80 shafts J J, respectively, and thus elevate the cover, as shown in Fig. 1. It is obvious that the raising of one cover only, as shown, is sufficient to enable said car to be loaded from a chute. 85

If desired, counter-weights L, Figs. 3 and 4, may be placed upon the arms g g upon one end of the car, in which case the hand-wheels K K may be dispensed with at that end; or, if preferred, said counter-weights may be placed 90 at both ends of said car, and so arranged as to balance or nearly balance said covers, in either of which events said covers may be operated by one man.

Said weights may consist of heavy plates or 95 pieces of cast-iron bolted to said arms; or spiral or other springs may be used in lieu and as the equivalent thereof.

It is obvious, that in case the operating-arms are properly counterpoised or balanced, the 100 hand-wheels and chains for operating them may be dispensed with, and projecting han-

dles attached to said arms at equal distances from the axis of said levers, by which the covers may be moved.

Having thus described my invention, what I claim, and desire to secure by Letters Patent, is—

1. A car-cover consisting of slanting hinged lids extending lengthwise of the car and hinged at or near the running-board, said covers being operated by means of bent levers having chains attached to their extremities, and trained over suitable shafts at the end of the car, the latter being provided with hand-wheels, substantially as and for the purposes specified.
2. The combination, with the body of a car, of the hinged lids H H, rigidly connected with the bent levers G G, chains I I, and shafts J J, with means for revolving said shafts and temporarily locking the same in position, substantially as described.

3. The combination, with the body of a car, of a stationary central running-board having one or more supports, E, sloping lids H H, operated by means of bent levers G G, chains 25 for connecting the same with suitable winding-shafts, J J, and means for operating said shafts, substantially as described.

4. The combination, with the body of a car, of the hinged lids H H, rigidly connected with 30 the bent levers G G, provided with counter-weights L, chains I I, shafts J J, and hand-wheels for operating and means for locking the same in position, substantially as and for the purposes specified.

JNO. H. GAGE.
